UNITED STATES PATENT OFFICE.

JESSE JORDAN AND OSCAR F. LAGERQUIST, OF MACON, GEORGIA.

SEAL-LOCK.

SPECIFICATION forming part of Letters Patent No. 328,893, dated October 20, 1885.

Application filed June 11, 1885. Serial No. 168,376. (Model.)

To all whom it may concern:

Be it known that we, JESSE JORDAN and OSCAR F. LAGERQUIST, citizens of the United States of America, residing at Macon, in the 5 county of Bibb and State of Georgia, have invented certain new and useful Improvements in Seal-Locks; and we do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 Our invention relates to certain new and useful improvements in seal-locks for car-doors, the object of our improvement being to provide a fastener for car-doors and a receptacle for a seal by means of which when the 20 door is opened the seal will be torn and destroyed; and to this end our invention consists in the construction of the hasp, lock, seal-receptacle, and covering-plate, the parts being constructed, combined, and organized, as will 25 be hereinafter set forth and claimed.

In the accompanying drawings, which illustrate our invention, Figure 1 is a perspective view showing the car-door closed and the door of the seal-cover open, so as to better illustrate 30 the interior construction of our improvement. Fig. 2 is a horizontal sectional view. Fig. 3 is a vertical sectional view taken through the line xx of Fig. 1. Fig. 4 is a detail perspective view of the hasp.

35 In the accompanying drawings, which illustrate our invention, A represents the sliding door of the car, and B the frame of the door against which the sliding door abuts. To the door-frame B is pivotally attached, by means 40 of a bolt, b, the hasp C, which hasp is raised so as to project beyond the edge of the door by means of a washer, b', which is placed under said hasp. A block or rest, c, projects from the door-frame and forms a rest for said hasp, 45 so as to hold it in a nearly horizontal position and on a line with the opening in the lock-case. The end of the hasp C through which the bolt b passes is provided with a slot, c', which will allow said hasp to be adjusted when 50 resting upon the block c, so that its end will

be on a direct line with the opening in the lock.

The lock consists of three parts, which are indicated, respectively, by the letters D, E, and F. The rear plate, D, has on its rear 55 surface, which is otherwise plain, a projecting portion, D', having inwardly-projecting walls, which extends through the frame-work of the car-door, forming thereby an opening through which a latch or pivoted catch, as will be hereinafter described, passes. The upper portion of the plate D has formed integral therewith a projecting ledge, d, which is sloped from its upper edge downwardly, so as to readily shed 60 water, said ledge being of sufficient width to extend entirely over the lock, and said ledge is provided with an upwardly-projecting portion, d', which is provided with a circular opening, through which the hasp of a padlock 65 may be passed. Adjacent to this upwardly-projecting portion d' is located a spring-catch, g, which is held thrown down by a spiral spring, g'. The upper portion of the rod of 70 this catch has attached thereto a finger-piece, G, for lifting the same, and said finger-piece is 75 provided with an opening which corresponds with the opening in the upwardly-projecting portion d', so that the parts can be immovably attached to each other. The lower face of the catch g is beveled, so that the hasp or latch-bar 80 C will raise the same when slipped into position.

The rear face of the plate or portion E of the lock is provided with a horizontal recess, e, which is of about the same width as the 85 thickness of the portion h of the hasp C, and the upper portion of this recess e is met by a horizontal groove or slot, e', which extends entirely through the plate E of the lock, and into said portion the thicker part h' of the 90 latch will pass. Immediately above the slot e' is a vertical groove, i, within which plays the sliding catch g. The length of the plate E of the lock is such that it will extend from the edge of the lock, which is adjacent to the 95 hasp C to the projecting portion D' of the back plate, D, and on its lower edge is formed a projecting portion, i', which extends on a line parallel with the flange d.

The parts D E are held securely to each other 100

by means of screws located on the rear or inner portion of the lock.

In the front face of the plate E of the lock is formed a recess, K, which is intersected or 5 traversed by the slot e', and the side wall of this recess adjacent to the upper edge of the slot is beveled, as shown in Fig. 1, so as to provide a cutting-point, k, against which the seal or label, which is placed in the slot or 10 opening o of the hasp and rests within the recess, will contact when said hasp is drawn outwardly, as will be hereinafter set forth.

The plate E of the lock is provided with perforations which correspond, as to locality, 15 with perforations in the plate D, said perforations being adapted to receive screws for the attachment of the lock to the car-door.

The hinged door or covering-plate of the lock is pivotally attached to the forward end 20 of the plate E by a pintle, f, and the inner face of said door is provided with a recess, j, beneath which there is an opening which extends entirely through this hinged portion, said opening being opposite the label-receptacle 25 of the lock. Within the recess j is secured a glass, j', which is suitably retained therein, and is covered, when desirable, by a hinged door, m, the hinge being located at the upper edge thereof, so that said door will normally 30 hang over the glass j'.

The outer edge of the hinged door F is provided with an inwardly-projecting portion, F', which is hollow, for the reception of a pivoted latch, L, the inner end of which is provided 35 with a hook, which engages with a cross-bar, l, located in the portion D', and said hook has an extended end, l', which is adapted to serve as a thumb-piece for raising said latch. The projecting portion F' of the door enters the 40 recess D', as shown in Fig. 2, and the flange n forms a rest or bearing which abuts against the adjacent flange formed on the back plate, D.

In Fig. 4 of the drawings I have shown the hasp C in a reversed position, said hasp having a raised portion, h', projecting from the 45 upper edge of the same outwardly, and through this raised portion is formed a slot or opening, o, into which the seal or label T passes, and a catch or beveled recess, u, is also formed 50 in the upper edge of the hasp C, with which the spring-catch g engages, so as to retain the same in position.

The operation of our device is as follows: When the door of the car is closed, the hasp 55 C will enter the lock and be in the position shown in Fig. 1 of the drawings, after which a seal or label having the imprint of the station at which such closing was effected is inserted in the opening o. The latch L is then 60 placed vertically in its recess and the hinged door F closed, when said latch will fall automatically and engage the cross-bar b, thus securing said hinged door in its closed position. If desirable, the spring-catch may be held in 65 place by a padlock. When the car reaches its destination, the label, if intact, shows that

the door has not been opened, and when said door is opened and the hasp C withdrawn from the lock said movement will sever the ticket and destroy the same, and the door F 70 can only be opened or released from the inner side of the car by raising the latch L, the portion l' of which extends to the interior of the car.

By the invention hereinbefore described, it 75 will be seen that the car-door cannot be opened without breaking the seal, and said seal cannot be replaced or exchanged without first opening the car-door; also, that by the construction of the casing the seal-receptacle 80 is protected from the weather.

By means of the invention hereinbefore described it can be readily ascertained that the car-door has been opened, and the point on the road where the seal has been broken can be 85 readily ascertained.

We claim—

1. In a lock for car-doors, the plates D E, secured to each other and provided with a spring-catch, the plate E provided with the 90 seal-receptacle, and a door hinged thereto and having an opening opposite the seal-receptacle, in combination with a hasp adapted to slide within the casing and provided with an opening for the reception of the seal or label, so 95 that the same will be destroyed when the hasp is withdrawn, substantially as shown.

2. In a lock for car-doors, a rear plate provided with a spring-catch, the plate E, recessed and slotted for the reception of a hasp 100 and having a recess, K, in the front portion thereof, and a hinged door or covering-plate having a pivoted latch adapted to engage with a cross-bar on the rear plate, in combination 105 with a hasp adapted to slide within the casing and provided with an opening for the reception of the seal or label, substantially as shown, and for the purpose set forth.

3. The combination, with a casing constructed substantially as described, of a hasp 110 adapted to be pivoted to the door-frame opposite the casing, said hasp having a projecting portion, h', opening o, formed therein, and a beveled recess, u, for the reception of the seal, substantially as shown. 115

4. In a lock for car-doors, a rear plate, provided on its upper edge with a projecting flange, having an upwardly-projecting portion, d', integral therewith, a vertically-moving spring-latch, inwardly-projecting 120 walls between which is located a cross-bar, the plate E, having a transverse slot and vertical and transverse recesses on its inner face, its outer face recessed to form a receptacle for a seal, said plate having attached thereto a 125 hinged door with an opening therein, said hinged door carrying a latch which is adapted to automatically engage with the cross-bar, and a hasp, C, the parts being organized and constructed substantially as shown, and for 130 the purpose set forth.

5. In a lock for car-doors, constructed sub-

stantially as described, the plates D and E, the latter having a transverse slot and recessed on its front face and provided with a beveled projecting portion, *k*, in combination with the hasp C, having an opening, *o*, the parts being constructed substantially as shown, and for the purpose set forth.

In testimony whereof we affix our signatures in presence of two witnesses.

JESSE JORDAN.
